UNITED STATES PATENT OFFICE.

ALBERT TEICHMANN, OF ZEITZ, GERMANY.

SAFETY DEVICE FOR ELEVATORS, CONVEYERS, AND LIKE APPARATUS.

Application filed February 16, 1925. Serial No. 9,628.

To all whom it may concern:

Be it known that I, ALBERT TEICHMANN, a citizen of the German Republic, residing at Zeitz, Germany, have invented certain new and useful Improvements in or Relating to Safety Devices for Elevators, Conveyers, and like Apparatus, of which the following is a specification.

This invention relates to a safety device for protecting elevators or the like from fire or accident. The protective device for this purpose differs from known devices in that the conveyer band is provided with abutment members which, in the event of the band stopping, suddenly disengage a coupling mounted inside the pulley which carries the band, so that only the shaft driven by the belt pulley continues to run. Further features of the invention comprise details relating to the abutment members and the coupling. A still further characteristic of the invention resides in the abutment members and coupling being duplicated and spaced at equal distances from the middle wall of the band-pulley, with a view to increasing the certainty of operation.

Two embodiments of the invention are shown by way of example in the accompanying drawings, wherein:

Fig. 1 is a front elevation of the pulley carrying the band.

Fig. 2 a vertical section on the line *a*—*b* in Fig. 1, the right half of the figure showing in elevation the inside construction of the pulley.

Fig. 3 a front elevation of a modified device, and

Fig. 4 a vertical section on the line *c*—*d* in Fig. 3, also with an elevational view at the right of the figure.

Referring to the drawings, the shaft 1 is journaled as usual in the head of the elevator and is rotated by a belt or the like from a pulley not shown. On the shaft 1 shown a sleeve 2 is held by screws and provided at both ends with flanges 3, on which sleeve the hub 4 of the pulley 5 may run freely. In order to mount the hub 4 on the sleeve, the latter is split in the middle. The band-pulley 5, or so-called "head-pulley" in contra-distinction to the pulley (not shown) at the foot of the elevator, has a central wall 6 into which are rigidly inserted the several pins of the disengaging device.

The endless band 7 carrying the buckets or other lifting receptacles 8 is stretched

over the pulleys at the top and bottom of the elevator and is provided with lugs 9 serving as abutment members and spaced at certain distances from one another, which lugs 60 form the ends of a narrow plate 10 secured transversely to the band. With this arrangement the plate 10 may be located between a bucket 8 and the band 7 and be screwed to these parts, as may be seen from Figs. 1 and 2. The abutment members may however be mounted on the band 7 independently of the buckets and have a form differing from that shown in the drawings so long as they fulfill the end in view.

In the flange 3 of the sleeve 2 is provided a groove 11 into which a tooth 12 of an L-lever pivoted on the pin 13 engages. The arm 14 is connected to a retracting spring 16 and the arm 15 is located below a lever 17, the pivotal pin 18 of which, like the pin 13, is journaled in the wall 6 of the pulley, and the pin 19 at the other end of which is pivoted to a thrust bar 20 which is pivoted to the pin 21 of a tappet lever 23 80 turnable on the pin 22 likewise securely connected to the pulley 5 or its hub 4.

The band-pulley 5 is conveniently balanced by means of a mass 24. It is advantageous to duplicate the abutment members, L-levers and all appertaining elements and to arrange them at equal distances from the middle wall 6.

The ends of the lever 23 and lugs 9 are wedge-shaped.

The operation of the device is as follows:

If during normal operation the band 7 and pulley 5 run at equal speeds the abutment members on the band and the tappet end of the lever 23 do not engage one another; even should the band 4 slip slightly, disengagement of the coupling, is not possible because should the band slip only slightly on the pulley 5 the lever 23 will yield somewhat when it engages the lugs 9, but 95 before disengagement of the coupling takes place the lug 9 will, if the slipping is slight enough, pass downwards out of engagement with the lever 23 which will then return to its normal position. On the other hand, the 100 effect is different should the band remain stationary as the result of a blockage in the elevator or for some other reason. In this case the abutment member 9 coming at the 105 moment into consideration engages against the lever 23, so offering a positive resistance, and since the lever is driven by the pulley 110

5 which continues to turn in the direction shown by the arrow, the said lever is turned on the pin 22 into the position shown by dotted lines. Hereby it displaces the thrust 5 bar 20 and the latter the lever 17. This lever 17 depresses the arm 15 of the L-lever and the arm 14 of the latter moves the tooth 12 from the groove 11. In this way, the coupling is disengaged; the pulley 5 is then 10 freely mounted on the sleeve 2 and the shaft 1 alone continues to run. As is clear from the disengaged position shown by dotted lines, the lever 17 reaches a dead-point in its extreme position and consequently the retracting spring 16 cannot return the tooth 12 which had before been engaged in the groove 11 unless the mechanism described is retracted into its initial position (engaged position) by hand or in some other way.

15 Since the abutment members 9 embrace the opposite edges of the pulley the band is continually guided on the pulley by said members, whereby laterally slipping of the band and likewise the danger of fire resulting therefrom are avoided.

20 The embodiment shown in Figs. 3 and 4 differs from that first described mainly in that the L-lever 14^a is simplified and by means of its tooth 12 engages in the groove 11 of the flange 3 of the sleeve 2 from above and not from below. In this modification said lever is provided with an elongated hole 25 for receiving the pin 26 of the tappet lever 23^a pivoted on the pin 22^a. In this way 25 the thrust-member 20 of the first embodiment is dispensed with. That arm 17^a of the lever 23^a which serves as a link in this case takes up a dead-point position when the coupling is disengaged.

25 I claim:—

1. A safety device for elevators, conveyers and power transmission belting comprising in combination with a driving shaft, a band pulley loosely mounted on said shaft, a band guided over said pulley, abutment members on said band and projecting over the rim of said pulley, a coupling mounted inside said band pulley and connecting the hub of said pulley with said shaft, and means in said pulley projecting into the path of said abutments and designed to be operated by said abutments when the band stops to disengage said coupling.

2. A safety device for elevators, conveyors and power transmission belting comprising in combination with a driving shaft, a belt pulley loosely mounted on said shaft and a band on said pulley, a hub on said pulley, a sleeve on said shaft serving as bearing for said hub of the pulley, a flange on said sleeve said flange having a groove, abutment members on said band, a tooth coupling mounted inside said band pulley and consisting of an L-lever, a tooth on said L-lever engaging 60 with the groove of said flange of said sleeve,

a retracting spring controlling said lever, a link lever contacting with said L-lever, a tappet lever connected with said link lever, said tappet lever being rocked by one of said abutments at the stopping of the band so 70 that said coupling is disengaged and said L-lever and link lever take up a dead-point position after disengagement.

3. A safety device for elevators and power transmission belting comprising in combination with a driving shaft, a belt pulley loosely mounted on said shaft and a band on said pulley, a hub on said pulley, a sleeve on said shaft serving as bearing for said hub of the pulley, a flange on said sleeve said flange having a groove, abutment members on said band, consisting of turned up ends of plates fixed on said band, a tooth coupling mounted inside said band pulley and consisting of an L-lever, a tooth on said L-lever engaging with the groove of said flange of said sleeve, a retracting spring 75 controlling said lever, a link lever contacting with said L-lever, a tappet lever connected with said link lever, said tappet lever being rocked by one of said abutments at the stopping of the band so 80 that said coupling is disengaged and said L-lever and link lever take up a dead-point position after disengagement.

4. A safety device for elevators, conveyers and power transmission belting comprising in combination with a driving shaft, a band pulley movably mounted on said shaft and a band guided on said pulley, buckets on said band, abutment members on said band 100 and consisting of the turned-up ends of plates fixed on said band, said plates being located between the band and each bucket, screws for uniting the band with the plates and the buckets, a coupling mounted inside 105 said band pulley and connecting the hub of said pulley with said shaft, and means in said pulley and projecting into the path of said abutments and designed to disengage said coupling when the band stops.

5. A safety device for elevators, conveyers and power transmission belting comprising in combination with a driving shaft, a band pulley movably mounted on said shaft, a partition on said band pulley, a band guided 115 on said pulley, abutment members on said band, a coupling mounted inside said band pulley at the one side of said partition and connecting the hub of said pulley with said shaft, means on said pulley at the one side 120 of said partition and projecting into the path of said abutments, a similar coupling in said pulley at the other side of said partition, and similar means in said pulley at the other side of said partition and projecting 125 into the path of said abutments, both said means being designed to disengage said couplings when the band stops.

In testimony whereof I affix my signature,

ALBERT TEICHMANN,
